INVENTOR:

Frederick Maussner

BY *Fr. DeWitt Goodwin*
ATTORNEY

UNITED STATES PATENT OFFICE.

FREDERICK MAUSSNER, OF COLLINGSWOOD, NEW JERSEY, ASSIGNOR TO HENRY WILHELM COMPANY, OF PITTSBURGH, PENNSYLVANIA.

MATTRESS.

1,423,954.

Specification of Letters Patent. Patented July 25, 1922.

Application filed July 10, 1920. Serial No. 395,324.

To all whom it may concern:

Be it known that I, FREDERICK MAUSSNER, a citizen of Germany, residing at Collingswood in the county of Camden and State of New Jersey, U. S. A., have invented certain new and useful Improvements in a Mattress, of which the following is a specification.

My invention relates to improvements in mattresses, cushions and the like. The object of my invention is to construct a mattress or cushion in sections, said sections each being provided with removable filling portions which are interchangeable, thus permitting a filling portion, which has become compressed from use in the mattress, to be shifted to a different position in the mattress and one of the other filling portions which has had less use to be substituted therefor; a further object of my invention is to make the filling portions in separable layers so that said layers are interchangeable with each other, and I also provide the mattress with a sheet of waterproof material located between the layers of the filling of the main section of the mattress, and a still further object of my invention is to construct the casing or ticking in separate sections or compartments, one of which is a multiple of a smaller compartment so that the filling portions may be used in either a large or small compartment and said compartments of the casing may be secured or hinged together so that the mattress may be readily folded into a compact form for handling.

Referring to the accompanying drawing: Fig. 1, is a sectional perspective view illustrating my improved mattress; Fig. 2, is a view similar to Fig. 1, showing the mattress in the folded position; Fig. 3 is a longitudinal section of the mattress showing the filling portions in a different position; Fig. 4, is a longitudinal section of the mattress showing a different form of filling portions; and Fig. 5 is a longitudinal section of a modified form of mattress embodying my invention.

In the drawing, in which like reference characters refer to like parts, 1 represents the casing, or ticking, forming the mattress or cushion. The casing 1 is divided throughout its length into sections, or compartments, 2, 3, and 4. The central or main compartment

3 is made twice the dimensions of an end compartment 2 or 4, so that the filling portions 12 and 13 may be interchangeably used in the different compartments.

The top sheet of fabric 6 of the casing 1 is preferably made in one continuous piece, extending over all the compartments to insure an even surface for the mattress and said sheet of fabric 6 forms a means for securing the sections of the mattress together, so that they may be folded into the position shown in Fig. 2, in which the mattress may be conveniently handled. The sections or compartments may be made separately if so desired without departing from my invention, or secured together in any desired manner.

Each section or compartment of the casing is made with one edge thereof provided with flaps 8, secured together by fastening devices, 9, as shown in Figs. 1, and 2; thus providing openings for the insertion and removal of the filling portions 12 and 13.

The filling portions are made in layers of one-half the thickness of the mattress so that either two layers may be used, one on top of the other, or only one large layer used by folding it upon itself; thus giving a double thickness to the filling portion.

Each layer of the filling portions 12 and 13 consists of hair, or fiber, 15, secured upon fabric, such as a sheet of burlap 16, by interlacing the hair or fiber upon the burlap in a manner well known to those skilled in the art. The sheets of burlap will hold the hair or fiber, when interlaced thereon, in a compact form so that a filling portion may be readily inserted or removed from a compartment of the casing.

The filling portions are preferably made as shown in Fig. 1, in which the filling portions 12 for the end compartments 2 and 4 of the casing are made co-extensive in size therewith, and the filling portions 13, for the central or main compartment 3, are made co-extensive in size with the latter compartment. One of the larger sized filling portions 13 may be used flat in the main compartment 3 of the casing or it may be used in the end compartment by folding said filling portion upon itself, so that it will readily enter and fill the smaller compartment of the casing, as shown in Fig. 3.

In Fig. 4, the filling portions 20 are shown to be all of the same dimensions. The filling portions 20 are used in the large compartment of the casing by placing said filling portions edge to edge in the same horizontal plane.

Fig. 5, illustrates a mattress casing formed in two compartments, 22 and 23 the larger of which is a multiple of the smaller and the 10 filling portions 25 are of the same size as the larger compartment of the casing. When used in the smaller compartment 23 one layer 25 of the filling portions is doubled over upon itself and it may be thus readily placed in 15 the smaller compartment of the casing.

A sheet of water-proof material 30 is placed in the mattress between the upper and lower layers of the filling portions of the main compartment of the mattress. Thus 20 providing a mattress suitable for use in hospitals. By positioning the sheet of water-proof material 30, in the mattress in this manner, any moisture will be confined to the upper layer of the filling material, and the 25 latter may be removed and cleaned without the necessity of cleaning the other filling portions of the mattress.

Having thus described my invention I claim and desire to secure by Letters Patent:

1. A mattress or the like comprising, a 30 casing divided into sections each of which forming a compartment, said sections adapted to be arranged edge to edge, one of said compartments being a multiple of a smaller compartment, removable filling portions arranged 35 in superimposed layers within each compartment, and said filling layers adapted to be interchangeable by placing the upper or lower filling layer of the smaller compartment in the same plane to form an upper 40 or lower filling layer for the larger compartment and by placing an upper or lower filling layer of the larger compartment in different planes within the smaller compartment to form upper and lower filling layers. 45

2. A mattress comprising, a casing divided into separate compartments adapted to be arranged edge to edge, one of said compartments being a multiple of a smaller compartment, removable filling portions arranged 50 in superimposed layers adapted to be interchangeable within said compartments, and one of said layers of the filling being co-extensive in size with the larger compartment and adapted to be folded upon itself and occupy the smaller compartment of the casing. 55

In testimony whereof I affix my signature.
FREDERICK MAUSSNER.
